UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

STEREOTYPE-PLATE CASTING AND FINISHING APPARATUS.

Continuation of application Serial No. 39,449, filed July 12, 1915. This application filed June 9, 1917. Serial No. 173,903.

To all whom it may concern:

Be it known that I, HENRY F. BECHMAN, a citizen of the United States, residing at Battle Creek, in the county of Calhoun and 5 State of Michigan, have invented certain new and useful Improvements in Stereotype-Plate Casting and Finishing Apparatus; and I hereby declare that the following is a full, clear, and exact description thereof, 10 reference being had to the accompanying drawings, which form part of this specification.

This invention is a novel apparatus or machine for casting and finishing stereotype plates such as are used on printing presses, and particularly tubular stereotype plates of the type shown in my Patent No. 867,230 dated October 1, 1907. The present 15 application is in part a continuation of my original application for patent filed July 12, 20 1915, Serial No. 39,449.

One object of the present invention is to enable such tubular plates to be cast and trimmed ready for use on the press with a minimum of manual handling. For this 25 purpose the apparatus is so constructed and arranged that after the plate is cast the core of the casting box is lowered to present the plate thereon to the trimming mechanism so that as the plate is removed from the core 30 it enters the plate trimming mechanism, and when withdrawn therefrom it is ready for placing upon the plate cylinder of a press, no boring of such plates being required because they are cast of the proper diameter 35 and uniform thickness.

Another object of the invention is to provide a plurality of casting boxes mounted on a movable support and in such relation to the melting pot or pots that while a previously cast plate is being removed from the core of one box to the trimming mechanism another plate is being cast, or can be cast, in another box, so that the operations of casting and finishing plates may be performed simultaneously and thus a great deal of time saved in the manipulation or operation of the apparatus, and the production of plates greatly facilitated.

Another object is to provide a melting pot and a plurality of movable casting boxes

adjacent the melting pot so that the casting boxes can be successively or alternately brought into position for receiving a charge of metal from the melting pot to cast a 55 plate and then be moved out of the way; and while a plate is being cast in one box a previously cast plate may be removed from another box, so that the operations of casting and removing plates from different 60 boxes may be performed simultaneously.

In the preferred method of operating the apparatus the core of the casting box is utilized as a means for supporting and directing the cast plate from the casting box 65 into the plate trimming mechanism; and when the plate enters the plate-holder of such mechanism the operator, by simply shifting a controlling lever, starts the trimming mechanism into operation, whereupon 70 the plate is automatically expanded within the holder, then the trimmers are automatically advanced to cut off the sprue and bevel both ends of the plate, and at the end of the trimming operation the plate-holder is automatically stopped and backed up until it is in position to receive a newly cast plate 75 from the core, and the finished plate is released and may be removed from the holder; and can be ejected therefrom by the insertion of a newly cast plate thereinto.

The invention includes the novel combination of a tubular plate casting box with tubular plate trimming mechanism. It also includes a novel arrangement of plate casting means. The invention further includes other novel combinations of parts and details of construction as are hereinafter set forth.

I will explain the invention in connection 90 with the accompanying drawings which illustrate a practical apparatus for casting and trimming tubular stereotype plates, but the invention is not restricted to the particular construction of parts shown in said 95 drawings, and I therefore refer to the claims for epitomes of the novel combinations and features for which protection is desired.

In said drawings:

Figure 1 is a part sectional side elevation of a complete apparatus embodying the in-

vention, and showing in dotted lines the core of the casting box lowered into position to direct a plate into the trimming mechanism.

Figure 2 is a reduced top plan view of Fig. 1 partly broken away.

Figure 3 is an enlarged detail transverse section showing the gearing for shifting the boxes in Figs. 1 and 2.

Figure 4 is an enlarged top plan view of the trimming mechanism.

Figure 5 is a sectional view on line 5—5 Fig. 4.

Figure 6 is a top plan view of another arrangement of movable casting boxes.

Figure 7 is a side elevation of Fig. 6.

Referring to said drawings, A, A', designate casting boxes, and T designates the trimming mechanism; these are preferably mounted in determinate relative positions for co-operation as hereinafter explained.

Each casting box A may be of the general construction illustrated in my patent No. 995,655 of June 20, 1911, having a drag a, a cope b and a tiltable core c; such boxes are adapted to produce tubular stereotype plates with a longitudinal slot such as described in my Patent No. 867,230 aforesaid. The core c is enclosed between the cope and drag during the operation of casting a plate, and when the plate is cast it surrounds said core; after the box is opened the core is tilted outwardly so as to permit the plate to be withdrawn therefrom.

In the example shown the core can be tilted to horizontal position, as shown in Fig. 2, and indicated in dotted lines in Fig. 1, and the boxes are preferably located in or movable to such position that when the core is so lowered it lies in exact axial alignment with the rotatable tubular plate-holder T' of the trimming mechanism so that the cast plate, indicated at P, may be slid directly off the core c into such holder T', as more fully hereinafter explained.

The trimming mechanism illustrated comprises a rotatable plate-holder T' mounted in suitable bearings 2 on the base, and said holder is adapted to be rotated by suitable mechanism, preferably such as shown and described in my original application Serial No. 39,449, and requires no further explanation herein.

The plate-holder is provided with a bar 7 and is stopped in such position that the bar 7 will be in direct line with the rib c' on the core c, which rib produces a longitudinal slot in the cast tubular plate. Therefore when the core c of a casting box is lowered to the position shown in dotted lines in Fig. 1 the slot in the plate will be directly in line with bar 7 and the plate can be slid endwise directly off the core into the plate-holder, the slot in the plate accommodating the bar 7.

In the preferred arrangement shown in

Figs. 1 and 2 two similar casting boxes designated as A, A' are employed; these casting boxes are each fixed to a slideable support F which is slidably mounted on a suitable base E adjacent a melting pot D which may be of any suitable construction. This melting pot is shown in Fig. 2 as provided with two pumps C and C' and two spouts B and B'; these spouts extend toward opposite ends of the base E and in such position that when the slide F is in one extreme position the casting box A will be positioned beneath the spout B, as illustrated in dotted lines in Fig. 2, and in the other extreme position a similar casting box A' will be positioned beneath the spout B'. When the parts are in the position shown in Figs. 1 and 2 the casting box A will be in such position that its core c when lowered will be directly in line with the plate-holder of the trimming mechanism and the plate can be slid endwise from the core into the holder T' as stated. And during the time the plate is being removed from the casting box A, a plate is cast in the casting box A'. When the plate has been removed from box A the slide is moved to the position shown in dotted lines in Fig. 2 so as to bring the box A' into line with the trimmer, and bring box A under the spout B; and while a cast plate is being removed from the box A', another plate is cast in the box A.

The slide may be moved back and forth, at the proper time by any suitable power actuated means. As shown the slide F has a rack H on its under side which meshes with a pinion G on a countershaft G' journaled in suitable bearings attached to the base E, or other suitable support; and the shaft G' has a bevel-gear g' meshing with a corresponding bevel-gear i on a shaft I' also journaled in suitable bearings on or adjacent the frame E, and extending to one end of said base. Shaft I' has on its outer end a preferably worm gear I which meshes with a worm K on a shaft K' which may be driven by suitable belts and pulleys, or other prime mover. As shown the shaft K' carries two loose pulleys L, L' which can be driven in opposite directions by belts, not shown, and on the shaft K' is splined a double faced clutch whose members M, M' are respectively adapted to engage with clutch members on the opposed pulleys L, L'.

The clutch can be shifted so as to clutch either pulley L, L' to shaft K' and simultaneously disengage the other pulley, so that by properly shifting the clutch the shaft can be rotated in the direction desired; or when the clutch is shifted to an intermediate position the shaft K' will be stopped. As shown the clutch may be shifted by means of a lever m connected by levers and links m', m², m³ to a hand lever m⁴ pivoted on the base E in a position convenient for manipulation.

by the operator; and by properly shifting this lever the operator can drive the gearing and shift the slide to move boxes A, A' to any desired position lengthwise of the frame E; and thus can bring the desired box into casting position and simultaneously bring another box into plate removing position.

The trimming mechanism is stopped automatically with the bar 7 in the plate-holder 10 in line with the slot in the plate on the core, and when the core is lowered as shown in Figs. 1 and 2 the cast plate comes, slot uppermost, directly in line with the bar 7 in the holder, and it is only necessary to move 15 the plate horizontally off the core into the plate-holder.

Adjacent each end of the plate-holder are plate trimming or cutting tools 68 and 69 which are operated as described in my said 20 application.

Figures 6 and 7 illustrate a construction in which the casting boxes are mounted on a rotatable support instead of an a slidable support and two or more boxes can be 25 mounted on such support, each of these boxes may be constructed as previously described. Four boxes are shown in said figures mounted on a rotatable support F³ which is rotatably mounted on the base E³ and may be rotated by any suitable means. As shown the support F³ has a bevel gear H³ 30 on its under side which meshes with a pinion G³ on a countershaft G⁴ which is provided with a worm gear I³ on the outer end meshing with a worm K on a shaft K' which 35 carries a loose pulley L engaged by a clutch M which clutch may be shifted by means of levers indicated in the drawings substantially as shown in Figs. 4 and 5, similar parts 40 being similarly lettered. In this construction however it is not necessary to reverse the rotation of the support F³, consequently only one pulley and clutch need be employed. Further only one pump C and discharge 45 spout B³ need be employed with the melting pot.

As the support is turned each casting box is successively brought into position beneath the spout B³ for casting a plate, and while a plate is being cast in one box a previously 50 cast plate may be removed from the opposite box which is then in line with the plate trimming machine, so that when the core is lowered as indicated in Fig. 7 the cast plate 55 may be slid from such core directly into the holder of the trimming mechanism; with this machine one plate may be cast while one plate is cooling, and another plate is being removed, and still another box is being 60 made ready for the casting operation; while the plate removed therefrom is being trimmed, so that with this apparatus, Figs. 6 and 7, plates can be made even more rapidly than with the apparatus shown in Figs. 4 and 5.

Operation.

The core c is in vertical position within the closed box when a plate is being cast (see box A' Fig. 2); but after a plate is cast, and when the box is properly positioned opposite the trimmer, the core is lowered to the position indicated in dotted lines in Fig. 1 (see box A in Fig. 2); the plate-holder being normally held in a position in which bar 7 is in exact alinement with the slot cast lengthwise in the plate P as it lies on the horizontal core c.

After a plate has been cast and sufficiently cooled, the casting box is opened and the core tipped to a horizontal position (Fig. 1) and the tubular plate is then slid sprue first, from the core into the plate-holder, the sprue projecting out of the outer end of the cylinder.

The operator then moves the starting lever 56 and the gearing causes the holder T' to revolve rapidly, and as it revolves the plate is securely locked in place in the holder as described in my said application while it is being trimmed.

As the holder revolves the trimming tools 68, 69 are moved to cut off the sprue and trim the ends of the plate, and after their work is performed the tools rapidly recede 95 to their original positions. The trimmer goes through its operations automatically, when started, relieving the operator from further attention to the machine until the plate is trimmed and ready for removal.

While one plate is being thus trimmed the core c may be returned to position in the box, and a new plate cast. When the plate has been trimmed the holder is stopped and the trimmed plate can be removed, and a new plate inserted therein, and the foregoing operations repeated.

While I have shown and described a multiple of boxes employed in connection with a single plate trimming mechanism, which makes a highly efficient and rapid organization of plate casting and trimming mechanism; the movable boxes could be usefully employed in casting plates even if the plates had to be separately carried from the boxes to a plate trimmer separated therefrom. Furthermore the invention would be very useful in making and trimming plates if but one box was employed in connection with the trimmer, but by using a plurality of boxes many more plates can be produced in a given time.

What I claim is:

1. Apparatus for making and finishing tubular stereotype plates, comprising a plurality of tubular plate casting boxes, and plate trimming mechanism adapted to receive a tubular plate endwise from a casting box and trim same, and means for moving the boxes into and out of position to 125

deliver plates to the trimming mechanism, substantially as described.

2. Apparatus for making and finishing tubular stereotype plates, comprising a tubular plate casting box having a movable cylindric core around which the plate is cast, said core being movable to present the plate to the trimming mechanism and tubular plate trimming mechanism adapted to receive a tubular plate slid end-wise thereinto directly from the casting box core and trim same, substantially as described.

3. Apparatus for making and finishing tubular stereotype plates, comprising a tubular plate casting box, and a tubular plate trimming mechanism adjacent thereto, said casting box having a tiltable cylindric core around which the tubular plate is cast and said core adapted to be thereafter tilted so that the tubular plate can be slid endwise from the core directly into the trimming mechanism; and said trimming mechanism being adapted to automatically finish the tubular plate after the same is inserted therein.

4. Apparatus for making and finishing tubular stereotype plates, comprising a tubular plate casting box having a pivoted tiltable cylindric core around which the plate is cast, said core being adapted to be tilted so as to direct the plate when cast into the trimming mechanism; and a tubular plate trimming mechanism adjacent said casting box and so located that when the core is lowered the plate when slid off the core will enter directly into the trimming mechanism, substantially as described.

5. Apparatus for making and finishing tubular stereotype plates, comprising a plate casting box having a movable core around which the plate is cast, a plate trimming mechanism located adjacent the box in line with the core and having a plate holder, said core being adapted to carry the cast plate from a vertical position in the box into a horizontal position adjacent the said plate holder, so that the tubular plate when slid endwise from the core will enter the holder; and said plate trimming mechanism being adapted to automatically trim a plate entered therein during one cycle of operations.

6. Apparatus for making and finishing tubular stereotype plates, comprising a tubular plate casting box having a tiltable core around which the plate is cast; a plate trimming mechanism adjacent the box and in line with the core having a tubular plate holder; said core being adapted when tilted downwardly to carry the cast plate from the box into axial alinement with the said plate holder, whereby when the plate is slid endwise from the core it passes directly into the holder; and said plate trimming mechanism being adapted to automatically trim a

plate entered therein during one cycle of operations.

7. Apparatus for making and finishing tubular stereotype plates, comprising a plurality of plate casting boxes, each casting box having a movable part adapted in one position to assist in the formation of a plate and in another position to carry such plate out of the box in position to direct such plate into the trimming mechanism; with a plate trimming mechanism; and means for moving the boxes into and out of position to deliver plates therefrom to said trimming mechanism.

8. Apparatus for making and finishing tubular stereotype plates, comprising plate casting boxes, each casting box having a tiltable core adapted in one position to assist in the formation of the plate and in another position to carry the plate out of the box and to direct the same into the trimming mechanism; and a tubular plate trimming mechanism adapted to automatically finish the plate after the same is inserted therein; with means for moving the boxes into and out of position to deliver the plates to the trimming mechanism.

9. Apparatus for making and finishing tubular stereotype plates, comprising tubular plate casting boxes, each having a core around which the plate is cast adapted in one position to assist in the formation of the plate and when moved to another position to carry the plate out of the box and to direct the same into the trimming mechanism; with a tubular plate trimming mechanism located in position to receive a plate from the core of a casting box and adapted to automatically finish the plate when the same is inserted therein; and means to supply molten metal to the boxes to cast plates therein, and means for moving the boxes alternately from casting position into position to deliver plates to the trimming mechanism, substantially as described.

10. Apparatus for making and finishing tubular stereotype plates, comprising a plate trimming mechanism having a tubular plate holder adapted to automatically trim a plate entered therein during one cycle of operations; and a plurality of plate casting boxes each having a movable core around which the plate is cast and adapted when lowered to direct the cast plate from the box into position adjacent the said plate-holder so that the plate when slid endwise from the core will enter the holder; with means for moving the boxes into and out of position to deliver plates to the trimming mechanism.

11. Apparatus for making and finishing tubular stereotype plates, comprising a plate trimming mechanism having a tubular plate holder adapted to automatically trim a plate entered therein during one cycle of operations; and a plurality of plate casting boxes

each having a movable core around which the plate is cast and adapted when lowered to direct the cast plate from the box into position adjacent the said plate-holder so that the plate when slid endwise from the core will enter the holder; with means for moving the boxes into and out of position to deliver plates to the trimming mechanism, means to supply molten metal to the boxes to cast the plates; and means for moving the boxes alternately from position to receive molten metal into position to deliver the plate, when the core is lowered, into the trimming mechanism, substantially as described.

12. Apparatus for making and finishing tubular stereotype plates, comprising a plurality of tubular plate casting boxes mounted upon a rotatable support, a plate trimming mechanism adjacent the support adapted to receive a tubular plate endwise from a casting box and trim same, and means for rotating the support to successively move the boxes thereon into position to deliver plates to the said trimming mechanism, substantially as described.

13. Apparatus for making and finishing tubular stereotype plates, comprising a plurality of individual plate casting boxes; each casting box having a movable part adapted in one position to assist in the formation of a plate and in another position to carry such plate out of the box in position to direct such plate into the trimming mechanism when the box is moved thereto; with a plate trimming mechanism beside the support and means for rotating the support to bring the respective boxes into and out of position to deliver plates therefrom to the said trimming mechanism.

14. Apparatus for making and finishing tubular stereotype plates, comprising a plurality of plate casting boxes each having a movable core around which the plate is cast and a rotatable support upon which the boxes are mounted, a plate trimming mechanism located adjacent the support and having a plate-holder, and means for rotating said support to bring the boxes successively into position to deliver plates to the trimming mechanism, the core of each box when opposite the trimming mechanism being adapted to carry the cast plate from a vertical position in the box into a horizontal position adjacent the said plate-holder, so that the tubular plate when slid endwise from the core will enter the holder; and said plate trimming mechanism being adapted to automatically trim a plate entered therein during one cycle of operations.

15. Apparatus for making and finishing tubular stereotype plates, comprising a plurality of individual tubular plate casting boxes, each casting box having a core around

which the plate is cast adapted in one position to assist in the formation of the plate and when moved to another position to carry the plate out of the box and to direct the same into the trimming mechanism; and a rotatable support for said boxes, with a tubular plate trimming mechanism located adjacent the support and adapted to receive a plate from the core of a casting box when the box is moved thereto and to automatically finish the plate when the same is inserted therein; means to supply molten metal to the boxes to cast plates therein; and means for rotating the support to move the boxes successively into casting position and then into position to deliver plates to the trimming mechanism, substantially as described.

16. Apparatus for making and finishing tubular stereotype plates, comprising a tubular plate casting box having a cylindric core around which the plate is cast, said core being movable from a substantially vertical to a substantially horizontal position and being vertical when the core is cast; with a substantially horizontal tubular plate trimming mechanism adapted to receive a tubular plate, slid end-wise thereinto directly from the casting box core when the latter is in a horizontal position, and to trim the plate; substantially as described.

17. Apparatus for making and finishing tubular stereotype plates, comprising a tubular plate casting box, and a substantially horizontal tubular plate trimming mechanism adjacent thereto, said casting box having a tilttable cylindric core around which the tubular plate is cast when the core is in a substantially vertical position, said core being adapted to be tilted to a substantially horizontal position so that the tubular plate can be slid endwise from the core directly into the trimming mechanism; said trimming mechanism being adapted to automatically finish the tubular plate after the same is inserted therein.

18. Apparatus for making and finishing tubular stereotype plates, comprising a tubular plate casting box having a pivoted cylindric tilttable core around which the plate is cast when the core is in a substantially vertical position; said core being adapted when lowered to a substantially horizontal position to direct the cast plate into the trimming mechanism; and a sub-horizontal tubular plate trimming mechanism adjacent said casting box and so located that when the core is lowered the plate when slid off the core will enter directly into the trimming mechanism, substantially as described.

In testimony that I claim the foregoing as my own, I affix my signature.

HENRY F. BECHMAN.
